PHOTOFILM LAMP

John H. Kurlander, Nutley, N. J., assignor to
 Westinghouse Lamp Company, a corporation of
 Pennsylvania

Application November 28, 1933, Serial No. 700,042

9 Claims. (Cl. 67—31)

This invention relates to a photoflash lamp and provides a rapid but intense source of illumination in the form of a flash for photographic purposes. Lamps of this character are at present in wide use and are known as photoflash lamps.

Photoflash lamps as shown and described in Reissue Patent 18,678 of December 6, 1932, comprises a clear glass bulb filled with several sheets of aluminum foil which are crumpled about a filament or heater element coated with a quick ignition material or primer so that when current passes through the filament and heats the primer the foil is ignited and the combustion is accelerated by the presence of pure oxygen with which the bulb is filled. The bulb is provided with the usual screw threaded lamp type of base and lead wires are provided having ends connected to the terminals of the heater element. These photoflash lamps are made either to operate at line voltage or by means of a battery in a holder having a socket for the lamp and a suitable switch. When a lamp is flashed, hot particles of melted foil are projected to the wall of the bulb which often cause cracking or breaking. The inside surfaces of the walls of the bulbs are, therefore, provided with an invisible layer of lacquer or cellulose to take the impact and dissipate the heat from the hot particles preventing breaks.

30 The foil in lamps now being used is, as above mentioned, loosely disposed in the bulb and when flashed the degree of illumination rises from zero in a quickly rising curve to what may be called a sharp peak and then tapers off to zero.

35 When taking a photograph with a photoflash lamp it is, obviously, desirable to operate the shutter of the camera at the high intensity point of the light. There is, however, a starting lag which must be considered and the duration of the 40 flash is so short, usually about .015 to .026 of a second including the lag, that means for operating a shutter at the instant the flash occurs, or preferably at the peak of the flash, requires delicate and accurate synchronizing mechanism.

45 This condition makes it difficult to obtain the best results and it is especially necessary to provide photoflash lamps which will operate exactly alike. This is also a difficult condition to contend with from a manufacturing standpoint, particularly since photoflash bulbs are made to sell at a relatively low price and must be produced at a high rate of speed.

It is an object of the present invention to provide a photoflash lamp which will operate to give 55 a relatively high degree of light for a relatively long period as compared with lamps as heretofore employed.

Another object of the invention is to provide a photoflash lamp so constructed as to control the 60 combustion of the light-giving material.

Another object of the invention is to provide a photoflash lamp containing combustible light-giving material so arranged as to produce a prolonged concentrated flash.

Other objects and advantages of the invention will be more clearly understood by reference to the following description together with the accompanying drawing in which

Fig. 1 shows a photoflash lamp having the combustible material arranged and supported in accordance with the present invention;

Fig. 2 is a fragmentary enlarged view of the lamp showing the press and a supporting disk;

Fig. 3 is a view taken on line III—III in Fig. 1; and

Fig. 4 is a modified construction showing a bulb with two compartments to control the combustion of the light giving material.

A photoflash lamp constructed in accordance with the present invention may comprise a bulb 20 having the usual base 11 and a press 12. Extending upwardly from the press are conductive supports 12' and 13 connected to the terminals of a heater element or filament 14. The filament may be coated with a material termed a primer 25 which serves to ignite the combustible material which in the present case is aluminum foil 15. It has been found that when the foil is loose in the bulb it flashes instantaneously and in order to prolong the flash the selected embodiment of the 30 invention provides means for extending the flashing period by arranging the foil in a sinuous path. A selected means for accomplishing this is to provide a container for the foil in the form of a helix or other elongated shape tube 16 to give relatively 35 long length.

This tube or container may preferably be of a transparent material such as a sheet of transparent cellulose acetate of about three-quarters to one inch in diameter and it is possible to enclose a container about six inches long within the bulb. The foil may be crumpled and arranged in the container so that the volume of foil will be substantially uniform throughout the length of the container. It may not be necessary, however, to use a container of the greatest possible length and if desirable the container may be in the form of a cup or cylinder about equal to the distance between the press 12 and the top of the bulb. The container may be of a mesh material or may be a net of wide mesh which will hold the foil in a prearranged mass to prolong the flash period. If the openings in the container are large it may not be necessary to make the container of a material that will be destroyed in which case a wire cage may be used.

It has been found that good results are obtained by the use of a thin sheet of cellulose, as shown, which sheet may have perforations 17 to give 55 quicker action. When the foil is flashed the con-

tainer, which is a cellulose sheet, is shattered since the sheet may be very thin and relatively frail or frangible so that it will be destroyed without interfering with the action of the flash or 5 obscure the light.

When making photoflash lamps as heretofore constructed difficulties arose in the handling of the foil as when disposing it in the bulb. In the present construction the foil may be disposed in 10 the containers which are more easily handled for application to the bulbs. When a lamp is to be made a disk 18 is disposed on the press 12, holes being provided in the disk through which the wires 12' and 13 extend. The filament may then 15 be secured to the said wires.

A container may then have an end 19 so disposed as to rest on the disk 18 and with the filament or heater surrounded by foil. A bulb may be placed over the container and sealed to a flare 20 tube 20 which carries the press 12. The device 25 may then be exhausted in the usual manner and supplied with the oxygen filling and sealed off.

When a lamp constructed in accordance with the present invention is operated the primer will 25 ignite the foil in the usual manner but instead of an instant flash the combustion will be progressive from the primer to the other end of the container and the length of the container will, therefore, determine the duration of the flash which 30 follows the path in the tube. The tube or container also serves to prevent hot particles of foil from being thrown against the glass bulb and thus avoids the necessity of the inside coating of lacquer to form a protective layer as above 35 mentioned.

The containers for the foil as constructed in accordance with the present invention greatly facilitate the manufacture of the lamp since the containers are what may be termed cartridges and 40 may be made up, handled, shaped and introduced into a bulb in a convenient and rapid manner which is not possible when introducing loose sheets of foil as in lamps as heretofore made.

It will be understood that the present photoflash lamp provides a source of illumination of the character of a flash but with what may be termed a flattened light intensity peak or light source whereas other lamps have a sharp peak i. e., high intensity of short duration, the present 45 lamp furnishes high intensity over a relatively long period. Thus the operation of a camera shutter during the high intensity light period is greatly facilitated and the extreme degree of accuracy as heretofore required is not necessary.

Although the structure and arrangement shown in Figs. 1 to 4 has given satisfactory results, it may be desirable to make a lamp as shown in Fig. 5, which comprises a bulb 25 of tubular form provided with the usual screw base 26. A pair 50 of lead wires 27 and 28 are connected to the terminals of a filament or heater 29. The bulb is divided into two compartments by a partition 30 of suitable non-combustible material such as asbestos. The lower compartment may contain 55 a quantity of aluminum foil 31 and the upper compartment may also be filled with a quantity of foil 32. The bulb may be provided with an atmosphere of oxygen to promote combustion. When the filament is energized to flash the foil 70 31 in the lower compartment of the bulb the intense rate of heat emission produced will ignite the foil 32 in the upper compartment although

the foil 32 is not electrically connected to a source of energy.

With the above construction the rate of combustion of the foil is controlled to give a relatively long period of intense flash and in some cases a bulb having a multiplicity of compartments containing foil may be employed. The degree of retardation of one flash behind the other may be controlled by the spacing between the individual fillings of foil. For example, the partition or washer 30 may be crumpled to take up more space to delay the action or two partitions may be employed with a space therebetween. 10

Although a preferred embodiment of the invention is shown and described herein, it is to be 15 understood that modifications may be made therein without departing from the spirit and scope of the invention as set forth in the appended claims.

What is claimed is:

1. A photoflash lamp comprising a bulb transparent to light rays, a quantity of combustible material within said bulb, means for igniting said material and combustible means for supporting the material as to control the rate of 25 combustion of said material when ignited.

2. A photoflash lamp comprising a transparent bulb, a quantity of aluminum foil within said bulb, means for igniting said foil and combustible means surrounding said foil for controlling the 30 rate of combustion of said foil.

3. A photoflash lamp comprising a transparent bulb, a quantity of aluminum foil within said bulb, means for igniting said foil and combustible means for confining said material to a relatively 35 narrow path.

4. A photoflash lamp comprising a transparent bulb, a quantity of combustible material within said bulb, means for igniting said material and combustible means for confining said material to a predetermined 40 path of combustion.

5. A photoflash lamp comprising a bulb, an elongated combustible chamber within said bulb to provide a long flashing period, a quantity of 45 aluminum foil in said chamber and means for igniting said foil.

6. A photoflash lamp comprising a transparent bulb, an elongated combustible tubular transparent container within said bulb to provide a long 50 flashing period, aluminum foil in said container and means for igniting said foil.

7. A photoflash lamp comprising a bulb transparent to light rays, a sinuous tubular container of transparent destructible material within said bulb, a filling of aluminum foil in said container 55 and means for igniting said foil.

8. A photoflash lamp comprising a bulb transparent to light rays, a sinuous tubular container of transparent destructible material within said bulb, a filling of aluminum foil in said container 60 and means disposed in said container for igniting said foil.

9. A photoflash lamp comprising a bulb transparent to light rays, a partition dividing the bulb into a plurality of compartments, said partition having a communicating aperture, a quantity of aluminum foil in each compartment, means for igniting the foil in one compartment whereby said ignited foil produces a flash and ignites the foil in the other compartment to produce another flash. 70
